US0D1080182S

(12) **United States Design Patent** (10) Patent No.: **US D1,080,182 S**
(45) Date of Patent: ** Jun. 24, 2025

(54) **LACING COMPONENT**

- (71) Applicant: **Wolverine Outdoors, Inc.**, Rockford, MI (US)
- (72) Inventors: **Barry J. McGeough**, Santa Barbara, CA (US); **Marc R. Loverin**, Scituate, MA (US); **Hsiao Hsun-Ming**, Taoyuan (TW)
- (73) Assignee: **Wolverine Outdoors, Inc.**, Rockford, MI (US)
- (**) Term: **15 Years**

(21) Appl. No.: **29/848,804**

(22) Filed: **Aug. 5, 2022**

(51) LOC (15) Cl. **02-07**
(52) U.S. Cl.
USPC **D2/978**

(57) **CLAIM**

The ornamental design for a lacing component as shown and described.

DESCRIPTION

FIG. 1 is a front, top perspective view of a lacing component embodying the new design;

FIG. 2 is a back, top perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The figures show features in broken lines that form no part of the claimed design. The broken lines immediately adjacent the solid line portions of the design form the boundary of the design, with the broken lines forming no part of the claimed design.

1 Claim, 4 Drawing Sheets
